CATHODE RAY TUBE CIRCUIT

Herre Rinia, Eindhoven, Netherlands, assignor,
by mesne assignments, to Radio Corporation of
America, New York, N. Y., a corporation of
Delaware

Application March 18, 1939, Serial No. 262,615
In Germany March 8, 1938

4 Claims. (Cl. 250—27)

This invention concerns a circuit arrangement comprising a cathode-ray tube having a control electrode to which is supplied an alternating voltage, such as is used in television receivers and in measuring apparatus. The characteristic curve of such cathode-ray tubes which indicates the relation between the electron-ray current which will be called the anode current hereinafter, and the voltage set up at the control electrode, which will be called the control voltage hereinafter, generally has a non-linear shape and furthermore the slope of the characteristic curve is generally small (Fig. 1). Owing to this small slope it is not possible, by means of a degenerative back-coupling, such as is known from the amplification practice, to linearise the shape of the characteristic curve since for the obtainment of a sufficient degenerative back-coupling even a small mutual conductance requires the insertion of a very large impedance in the cathode lead of the cathode-ray tube. The self-capacity of this impedance preponderates in this case particularly at high frequencies of the control voltage, due to which substantially no back-coupling is obtained for these frequencies.

According to the invention this difficulty is removed by supplying the control voltage at the same time to the input circuit of a discharge tube in which the slope of the grid voltage/anode current characteristic is greater than that of the cathode-ray tube and in which a voltage is derived from the anode circuit of the discharge tube which is supplied in phase-opposition to the control voltage of the control electrode of the cathode-ray tube.

In describing the invention in detail, reference will be made to the drawing in which Fig. 1 shows the control voltage anode current characteristic of a cathode ray tube diagrammatically;

Fig. 2 shows in graphical form the grid voltage anode current characteristic a thermionic tube, while

Fig. 3 shows one embodiment of the invention in which a thermionic tube is connected in parallel with the cathode and control electrode of the cathode ray tube.

Preferably a discharge tube is used whose control grid voltage/anode current characteristic has a shape similar to that of the control voltage/anode current characteristic of the cathode ray tube (Fig. 2).

The invention will be more clearly understood by reference to Fig. 3 of the accompanying draw-

ing representing, by way of example, one form of construction thereof.

Fig. 3 shows a cathode-ray tube 1 comprising a cathode 2, a control grid 3, a first anode 4, and an anode 5 which may, for instance, be coated with fluorescent material. To the control electrode 3 is connected the control grid 6 of the discharge tube 7 whose cathode 8 is connected to the cathode 2 of the cathode-ray tube. The required anode-voltages for the tubes 1 and 7 are delivered by a supply 9.

The common cathode lead for the two tubes 1 and 7 includes a resistance 10. The control voltage E for the cathode-ray tube is applied between the control electrode 3 and the end of the resistance 10 remote from the cathodes 2 and 8.

To improve the characteristic curve of the cathode-ray tube it is necessary that a sufficient voltage is set up at the resistance 10, which voltage is supplied to the grid 3 in phase-opposition to the control voltage E. The voltage set up at the resistance 10 is substantially caused by the anode current of the tube 7 whose mutual conductance is greater than that of the cathode-ray tube. Consequently the resistance 10 may be much smaller than in the absence of the tube 7. The self-capacity of the resistance 10 may now also be neglected at high frequencies of the control voltage, thus obtaining a degenerative back-coupling which is independent of the frequency. If it is desired that the degenerative back-coupling should depend in a definite manner on the frequency the resistance 10 may be replaced by a suitable impedance.

Furthermore, it will be appreciated that suitable networks may be included in the connecting leads 11 and 12 between the control electrode 3 and the control grid 6, and the cathode 2 and 6 respectively, which networks may involve again a frequency-dependent degenerative back-coupling.

The form of construction described above includes a so-called negative current feed back by means of a resistance in the common cathode lead. It will be appreciated, however, that the same result can be obtained by means of a so-called negative voltage feed back in which the anode circuit of the discharge tube 7 comprises an impedance and the voltage set up across a part of this impedance is supplied to the cathode-ray tube in phase-opposition to the control voltage of the control electrode 3.

Furthermore the drawing shows a cathode-ray tube without a deflecting system; it will be understood, however, that any desired system may be used.

What I claim is:

1. In a cathode ray tube having a cathode, a control electrode, an anode and target electrode, the method of making the control electrode-anode current characteristic linear which comprises the steps of supplying control voltage to the control electrode and cathode, simultaneously deriving a voltage from the supplied control voltage, and supplying the derived voltage between said control electrode and cathode in anti-phase relationship to the supplied control voltage.
2. A cathode ray tube control system comprising a cathode ray tube having a cathode, a control electrode, an anode, and a target electrode, means to supply control voltage to said control electrode and to said cathode through a series resistance, a thermionic tube having a cathode, a grid and anode, connections from the control electrode to the grid and from the cathode of said cathode ray tube to the cathode of said therm-

ionic tube, and a voltage supply for supplying both of said anodes and said target electrode.

3. A cathode ray tube system comprising a cathode ray tube having an input circuit including a resistance, means to supply control voltage to said input circuit, thermionic means for deriving a voltage from said control voltage and connections from said thermionic means to said resistance to supply the derived voltage to said input circuit in anti-phase relation to the supplied control voltage.

4. A cathode ray tube system comprising a cathode ray tube having an input circuit including an impedance, means to supply control voltage to said input circuit, thermionic means for deriving a voltage from said control voltage, and connections from said thermionic means to said resistance to supply the derived voltage to said input circuit in anti-phase relation to the supplied control voltage.

HERRE RINIA.
